UNITED STATES PATENT OFFICE

WILLIAM E. SHORE, OF NEW YORK, N. Y.

OIL BURNER

Application filed October 29, 1924. Serial No. 746,553.

The principal objects of the present invention are to devise a form of burner particularly adapted for use in small plants such as for house heating and which will operate without noise at low flame velocity.

A further object is to devise a structure which will effectively burn any grade of oil or fluid hydrocarbon.

A still further object is to insure the entire body of hydro-carbon being subjected to a temperature that will completely break down its structure and effect complete combustion before the produced heat is transferred to the heat distributing medium.

15 The principal feature of the invention consists in arranging within the heating chamber of a furnace a preheating and gasifying chamber wherein the hydro-carbon is broken up and mixed with air at a high temperature to effect complete combustion before the products are delivered to the heating chamber in an incandescent state.

In the drawings Figure 1 is a vertical mid-sectional view of an apparatus constructed 25 according to this invention.

Figure 2 is a horizontal sectional detail taken on the line 2—2 of Figure 1.

Figure 3 is a horizontal sectional view taken on the line 3—3 of Figure 1.

30 Figure 4 is a horizontal sectional view taken on the line 4—4 of Figure 1.

Many different forms of apparatus have been conceived for the purpose of burning heavy hydro-carbons but much difficulty has 35 been found in accomplishing the desired result of complete combustion of the fuels so that the maximum of heat values would be recovered and the nuisance of smoke eliminated.

40 The present invention accomplishes the desired results by burning the fuels progressively before they are brought into contact with the heat transferring mediums.

In the form of apparatus herein illustrated 45 a circular pot 1, preferably having convergent side walls, rests on the base of the furnace 2, which is here shown as an ordinary type of hot water furnace.

A refractory wall 3 is built around the pot 50 and extends up to the ordinary grate ring 4

and is spaced from the pot to form an annular chamber therearound. The pot is preferably lined with refractory material 5. A pot 6 open at the bottom and having a plurality of perforations 6' in its wall is supported centrally of the pot 1 upon the radial arms 7 and is spaced from the inner wall of the pot 1.

An upright tubular member 8 is seated at its bottom end in an annular recess 9 in the top of the pot 6 and is formed with a plurality of inwardly projecting radial ribs 10 which are formed with shoulders 11 intermediate of their length, the top ends 12 of which project above the top of the tubular member. An elbow shaped cap 13 rests upon and forms a 65 continuation of the member 8.

A conical member 14 of refractory material open at the top and having a perforated wall rests on the shoulders 11 of the ribs 10 and extends upwardly into the cap 13.

70 Centrally above the member 14 is suspended a metal cone 15. This cone is formed with a central orifice 16 which extends to the top. A bolt 17 secured in the cap 13 and extending to the bottom of the orifice holds the cone in 75 place.

A tube 18 secured in the side opening of the elbow cap extends horizontally through the door opening 19 of the furnace and the oil feed pipe 20 connects with the orifice 16 of 80 the cone 15 and extends through said tube.

85 A tube 21 arranged below the tube 18 is connected with the elbow cap and a gas supply pipe 22 projects into the tube 21 from the outer end. A spark plug 23 is arranged at the inner end of the tube 21 to ignite the gas projected into the cap. The tube 21 is open at the outer end and forms a mixing chamber to mix air with the gas.

90 A pipe 23' is shown extending through the tube 18 and connected to a burner 24 supported from the cone 15. This is only used when gas is not available and it is adapted to carry a readily combustible oil, such as kerosene which may be ignited, to heat the main burner and produce and maintain a proper temperature for the gasifying of the heavier hydro-carbon fed to the cone 15.

100 The outer end of the tube 18 may be left

open for the free admission of air or it may be provided with a regulating damper 24.

If a forced draft is desired a blower of any suitable design may be arranged to discharge into the outer end of the tube 18.

5 Suitable electrical connections for operating the spark plug ignition may be arranged as desired, an installation being diagrammatically shown connected with the lever controlling the gas supply.

10 In the operation of this invention the fluid hydro-carbon which may be crude oil or fluid fats or tallow or other materials possessing hydro-carbon properties, is conducted through the pipe 20 to the oil chamber in the cone 15, it being fed either by gravity or under pressure as may be found desirable.

15 The oil rising in the orifice 16 flows over the top and down the surface of the cone and 20 drips from the bottom edge thereof upon the surface of the perforated refractory cone 14.

Prior to turning on the flow of heavy hydro-carbon, a flame is produced in the tube 21 by means of gas furnished from a suitable 25 supply and mixed with air in its passage through the tube which is open at the outer end. The gas mixture may be ignited in any suitable manner but a spark plug is here shown as a convenient means for lighting the 30 gas flame at the inner end of the tube 21. The spark plug is shown diagrammatically as being controlled by the gas lever, that is, when the gas is turned on the electric circuit to the 35 spark plug is closed and an ignition spark is created.

The flame projected from the inner end of the tube 21 into the vertical chamber enclosed by the upright member 8 and cap 13 heats the refractory cone member 14 and also heats 40 the metal cone 15 over which the oil is fed. This heat volatilizes certain portions of the constituents of the heavy hydro-carbon and ignites them and the heat produced augments the heat of the gas flame and volatilizes other 45 materials of the fuel of a higher flash point.

The combustion of the fuel is therefore progressive and as the natural draught of the furnace draws air in through the tubes 18 and 21 this air is drawn downwardly in the 50 upright tube 8 and is continually mixed with the volatilized fuels. The free carbon released in the combustion is carried downwardly and as the heat becomes more intense it becomes ignited.

55 It will be understood from this description that destructive distillation of the hydro-carbon is set up in the upright chamber enclosed by the tube 8 and cap 13 and that as the lighter portions of the hydro-carbons are 60 distilled off they combine with the air and increase the temperature within the chamber as the combustion proceeds down the column.

The fuel flows downwardly over the perforated cone 15 and as it flows the lighter particles are progressively extracted therefrom

and the heat produced continues to flow downwardly because of the natural direction of the draught while both the draught and the force of gravity carries the fuel onward. As the temperature rises a cracking of the 70 hydro-carbon occurs and the released free carbon is finally brought into a zone of high temperature where it is completely consumed.

The products of combustion flow from the vertical chamber out through the perforated 75 pot 6 and flow upwardly into the heat transferring chamber of the furnace where their heat is given off to the water chambered walls. The vital point is that complete combustion of the fuel takes place within a chamber enclosed within a heating chamber of the furnace before the products of combustion are 80 allowed to come into contact with the walls of the heat exchanging chamber which absorb the heat from such products of combustion, 85 consequently there can be no loss through the cooling of partially consumed particles volatilized or freed from the hydro-carbon fuel.

It may be found desirable to add a certain 90 amount of air to the products of combustion discharged from the vertical combustion chamber and in order to provide for this an air duct 25 is arranged in the wall 3 close to the base of the pot 1. Air entering this duct is directed around the base of the pot and is partially heated and rising in the annular chamber around the pot it is further heated before coming into contact with the actual flame emanating from the pot around the central column. This introduction of 95 hot air into the flame adds further oxygen thereto and ensures the complete consumption of any stray particles which may have escaped from the inner combustion zone. This auxiliary air would not be used under 100 conditions of a normal or low fire but would be used to augment a hot fire, as normally the amount of air taken in through the air tubes will be sufficient to completely consume all combustible material.

The result of the use of a structure such as described is that all the fuel will be completely burned, consequently the maximum of heat units contained in the fuel will be liberated. The consequence is that a very high 115 efficiency is obtained. It is of course readily understood that all heat applied to the central chamber is beneficial to the condition within the heat exchanging chamber, as a very considerable amount of heat will be radiated therefrom and there will be no loss.

When a fire has been started and the inner combustion chamber has been thoroughly heated to a temperature to ensure combustion of the particles the gas may be cut off. I have shown a burner arranged below the cone 15 to be supplied with a low flash hydro-carbon such as kerosene which may be used for starting. With this structure it is merely necessary that the use of the lighter oil 120

be continued until the chamber is raised to a sufficient degree of heat to thoroughly gasify the heavier oil.

It will be readily understood that many modifications may be made in the structure of the device herein disclosed without departing from the spirit of the invention so long as the construction provides a combustion chamber enclosed within the main heating chamber and in which the hydro-carbons are fed downwardly so that they are maintained in a highly heated zone without contact with cooled surfaces until the combustible material is completely consumed and the heat generated is then brought into contact with the heat transferring surfaces.

In a process of combustion as herein described the products to be burned are held in perfect suspension until prepared to assimilate themselves with the atmosphere for combustion, each atom burning according to its specific nature and speed of combustion. The cracking of the oil causes first the combining of the lighter or hydrogen bearing content which ignites at low temperatures and pressures and burns rapidly, producing high temperatures and the carbon produced igniting because of the raising of the temperature of one part of carbon so that it will combine with two parts of oxygen, which result would not be effected at low temperature.

What I claim as my invention is:—

1. In an oil burner, the combination with the combustion chamber of a furnace, of a pot in the bottom thereof having an open top, a perforated pot open at the bottom and top and of lesser diameter than the aforesaid pot supported from the top of the aforesaid pot, a tubular member extending upwardly from the top of the inner pot, a refractory obstructing member supported centrally of said tubular member and having a passage therearound, a cap closing the top of said upright tubular member, an oil distributing member supported within said cap centrally of the upright tube, a conduit leading from outside the furnace combustion chamber to said cap, an oil feed pipe leading through said conduit to the oil distributor, and means extending from outside the furnace combustion chamber into said cap for projecting a flame into the path of the distributed oil.

2. In an oil burner, the combination with the combustion chamber of a furnace, of an air conduit extending downwardly within said combustion chamber and directing a confined flow of air toward the lower end thereof, a hollow member arranged in said air conduit having the walls perforated to present an extended surface area, and means at the upper end of said air conduit for dropping oil in liquid form upon the perforate walls of said hollow member, said perforate walls effecting the suspension of

the liquid oil in the path of the confined downward flow of air within the air conduit to effect its progressive volatilization.

3. In an oil burner, the combination with the combustion chamber of a furnace, of an air conduit extending downwardly within said combustion chamber and directing a confined flow of air toward the lower end thereof, a hollow conical walled refractory member arranged centrally within and supported from the inner wall of said air conduit and being spaced therefrom to provide a free passage for the downward flow of air, and means at the upper end of said air conduit for dropping oil in liquid form upon the conical wall of said refractory member, said walls being perforated to provide an extended surface area to effect the suspension of the liquid oil in the path of the downward flow of air within the air conduit whereby to effect its progressive volatilization within the conduit.

4. In an oil burner, the combination with the combustion chamber of a furnace, of an air conduit extending downwardly within said combustion chamber and directing a confined flow of air toward the lower end thereof, a hollow member arranged in said air conduit having the walls perforated to present an extended surface area, means at the upper end of said air conduit for dropping oil in liquid form upon the perforate walls of said hollow member, said perforate walls effecting the suspension of the liquid oil in the path of the confined downward flow of air within the air conduit to effect its progressive volatilization, a baffle member below the lower end of said air conduit for receiving the discharge therefrom and having upwardly extending walls adapted to direct the burning gases upwardly around the outer wall of said air conduit, and a perforate walled member interposed between said baffle member and the lower end of said air conduit.

5. In an oil burner, the combination with the combustion chamber of a furnace, of an air conduit extending downwardly within said combustion chamber and directing a confined flow of air toward the lower end thereof, a conical oil distributing member supported in an upright position within the upper end of said air conduit, said conical member having an oil well therein extending centrally downwardly from the small upper end, said well being open at the top, means for conducting oil to said well at the lower end thereof, said oil being adapted to flow from the open top of the well down over the outer conical wall of the oil distributing member and drip from the lower end in a circumferential path, a hollow conical-walled refractory member supported in an upright position from the inner wall of said air conduit cen-

trally below said conical oil distributing member and having the upper portion of its wall arranged in the path of the oil dripping from said conical oil distributing member to intercept said oil, the wall of said refractory member being perforated to expose the maximum surface area and effect thereby the suspension of the intercepted liquid oil in the direct path of the downward air flow within the conduit to cause its progressive volatilization therein.
